FRED A. COOKE, OF SEATTLE, WASHINGTON, ASSIGNOR OF ONE-FOURTH TO MELLEN L. STICKNEY, OF SEATTLE, WASHINGTON.

GAME APPARATUS.

1,161,452.

Specification of Letters Patent.

Patented Nov. 23, 1915.

Application filed January 25, 1915. Serial No. 4,137.

To all whom it may concern:

Be it known that I, FRED A. COOKE, a citizen of the United States, residing at Seattle, in the county of King and State of Washington, have invented certain new and useful Improvements in Game Apparatus, of which the following is a specification.

This invention relates to improvements in games or puzzles and has for its object the provision of a game-board having a series of grooves or tracks formed therein for the accommodation of a plurality of balls which are adapted to be manipulated about said grooves according to various predetermined arbitrary rules, affording opportunity for the exercise of skill and dexterity either in competition with others, as in a game, or in solitaire.

A further object of the invention is the adaptation of a game-board having the physical characteristics of a baseball field, in combination with a plurality of balls representing players whereby an interesting, attractive and instructive game may be enjoyed.

The invention consists in the novel construction, adaptation and combination of a game-board, the balls provided therefor, together with devices for maintaining said balls in operative and visible condition, as will be fully described in the following specification illustrated in the accompanying drawings, and finally set forth in the appended claims.

Referring to said drawings, Figure 1 is a plan view of a game-board embodying my invention illustrated with the balls representing players associated therewith. Fig. 2 is a longitudinal sectional view taken 40 through dotted line 2-2 of Fig. 1.

Referring to said drawings, the reference numeral 4 designates the bottom of a containing case of rectangular or other suitable shape.

6-6 indicate the opposite side walls of said case, 5 the rear end wall, and 7-8 the opposite front end wall.

Slidable in grooves in said side wall 6 is a glass or other transparent plate 10 which is fixedly connected to the portion 8 of the front end wall and which is removable with said plate and provides facilities for readily removing and replacing the same in operative position relative to the case.

11 indicates the game-board proper consisting in a sheet of metal or other suitable material secured along its outer marginal edges in the fixed side and end walls of said case in spaced parallel relation between the bottom 4 and plate 10.

Arranged symmetrically in the upper surface of said board is formed a continuous channel 14 of quadri-lateral configuration, which represents the path between the bases in a baseball diamond, and commonly termed "the diamond." Said channels are arranged obliquely with respect to the longitudinal axis of the case and at the angles formed at the intersections of the channels forming the sides of said diamond, are arranged the bases, as ordinarily; the base nearest the forward end of the case being the home plate designated by the reference character H; the first base to the right-hand of the home plate is indicated by the character B¹; the second base, being that directly opposite the home plate, being indicated by B²; and the third base, to the left-hand of the home plate, being indicated by B³. Such bases are constituted by relatively slight circular depressions below the plane of the bottoms of said channels.

Branching from the home plate in approximately the longitudinal axis of the case, is a groove 15 of less width and depth than the adjacent said channels, terminating in a depressed circular pocket indicated by the reference character C, denoting the position of the catcher; extending in diametrically opposite directions from said groove 15 is a similar groove 16 terminating in a depression P, denoting the position of the pitcher; extending from said depression B² in diametrically opposite directions transversely to said longitudinal axis of the case are similar grooves 18 and 18¹ terminating at their outer extremities in depressions S and S¹, respectively denoting the positions of short-stop and second-baseman; extending in the longitudinal axis toward the rear end of the case from the depression B² is another similar groove 20 terminating in its outer end in a depression C¹, denoting the position of the center-fielder; extending from the depression B² in opposite rearwardly oblique directions relative to said longitudinal axis are similar grooves 21 and 21¹ terminating at their outer ends in de-

pressions L and R, respectively denoting the positions of the left-fielder and right-fielder.

The depressions L and B³ upon the left-hand side of the board, and the depressions 5 R and B¹, are connected by grooves 22 and 23, respectively, of similar configuration in cross-section to said groove 15. Said last-named grooves may be desirably curved in outward directions between their terminal 10 points, as indicated in Fig. 1.

Spherical balls of two different sizes and of contrasting colors may desirably be employed to represent the opposing sides of the player-men, the balls 17 being of relatively large size adapted to fit within and roll readily in the relatively wide channels 14 and may be termed the hitters or runners. The balls 19, denoting the player-men of the opposing side, or fielders, are of smaller 15 diameter than the balls 17 and are adapted to roll readily in all the grooves as well as the channels 14. The balls 17 being of greater diameter than the respective grooves, will not readily roll in the smaller grooves 20 from their normal path, the channel 14. The plate 10 and the board 11 are desirably spaced apart for a distance sufficient to allow the balls to roll freely within the grooves and channels, but are sufficiently close to 25 prevent the balls from rolling out of said grooves or channels; that is to say, the uppermost extremity of the balls is a lesser distance from the lower surface of plate 10 than the depth of the groove or channel.

When the game is to commence, the plate 30 10 is slidably removed from the case and the balls 19 are placed in their desired positions within the depressions or pockets at the termination of the respective grooves, and a larger ball 17 positioned at the depression H, denoting the home plate.

With the balls set in the positions or depressions heretofore described, the case is manipulated by tilting in any direction to 35 cause a larger ball, as 17, originally positioned at the home plate H, to roll along the first right-hand channel 14 toward the depression B¹, and thence about the circuit of the channel 14 back to said home plate H 40 without being touched by or colliding with any of the smaller balls 19.

It will be seen that the smaller balls may run readily in the channels 14, whereas the larger balls 17 cannot readily be directed out 45 of the circuit of the channels 14 into any of the grooves branching therefrom.

A game may readily be played upon the board by having a system of points for plays made and the board being used alternately 50 by the opposing sides, who manipulate the board to cause the larger ball 17 to course about the circuit of the channels 14 and score accordingly.

The game requires considerable skill and 55 dexterity to play successfully and is very

instructive and entertaining, particularly as it follows by relatively close analogy the plan and practice of a baseball game.

The rules and penalties of the game may be of great variety and will not be further 70 described here, excepting to say that in the use of the board as a puzzle or solitaire game, the number of balls and their positions may be increased or diminished as the skill of the player will justify. 75

Having described my invention, what I claim, is—

1. Game apparatus consisting in a board formed with a continuous groove or channel of quadrilateral configuration, and a plurality of grooves of smaller depth and width than said first named groove, connected with and branching from said first named groove, and a plurality of balls arranged to be rolled about said grooves. 80

2. Game apparatus consisting in a board formed with a continuous groove or channel of quadrilateral configuration, and a plurality of grooves of smaller depth and width than said first named groove connected with and branching from said first named groove, depressions formed below the plane of said first named groove at the intersections of said quadrilateral sides, and other depressions formed in the extremities of said second named grooves farthest remote from their connection with the second named grooves and a plurality of balls arranged to be rolled about said grooves. 90

3. Game apparatus consisting in a board 100 formed with a plurality of depressions spaced at relative distances to represent the stations of the players upon a baseball field, certain of said depressions positioned at the intersections of four straight lines forming 105 a quadrilateral figure having greater depth than the remainder of said depressions, and a plurality of grooves connecting said depressions, the grooves connecting said deeper depressions having correspondingly greater depth than the remainder of said grooves and balls of suitable sizes arranged to roll in 110 said grooves, respectively.

4. Game apparatus consisting in a casing 115 provided with a transparent plate forming its upper horizontal wall, a board in parallel with and spaced from said plate formed with a continuous groove or channel of quadrilateral configuration, a plurality of grooves of smaller depth and width than said continuous groove connected with and branching from said continuous groove, balls arranged to roll in said grooves when the board is inclined, the spacing between the board and said plate preventing the displacement of the balls from said grooves. 120

5. Game apparatus consisting in a board formed with a continuous groove or channel, a plurality of smaller grooves connected with said first named groove, and a plurality 125 130

of balls arranged to be rolled about said grooves.

6. Game apparatus consisting in a board formed with a continuous groove or channel, a ball adapted to roll in said groove, a plurality of smaller grooves connected with said first named groove, and a plurality of smaller balls arranged to roll in said last named grooves.
- 10 7. Game apparatus consisting in a board formed with a continuous groove or channel, a plurality of smaller grooves connected with said first named groove, said grooves having spaced depressions formed below the plane of said first named groove, and a plurality of balls arranged to be rolled about said grooves.
- 15 8. Game apparatus consisting in a board

formed with a continuous groove or channel of quadrilateral configuration, a depression in said groove at the intersection of each pair of adjoining ends of said groove, a ball adapted to travel in said groove when the board is inclined, a plurality of smaller grooves connecting with said first named groove and each formed with a depression at its extremity remote from said first named groove, and a plurality of balls adapted to travel in said last named grooves.

Signed at Seattle, Wash., this 15th day of January, 1915.

FRED A. COOKE.
